UNITED STATES PATENT OFFICE

DOUGLAS B. DENNIS AND CLAUD WILSON, OF TAFT, CALIFORNIA

FLUID ELEVATOR

Application filed August 9, 1927. Serial No. 211,790.

This invention relates to fluid elevators and has for its principal object to provide a simple, practical, and efficient construction adapted to raise oil, water, or other fluids from wells.

5 An additional object is to provide a device of this character which may be used in either deep or shallow wells, and embodying a construction employing the use of either gas, oil, water or other fluids for use as the lifting medium.

10 Another object is to provide a fluid elevator of the above-mentioned character comprising a fluid elevating apparatus including a lifting pipe arranged within a casing in spaced relation thereto and providing a passageway between the same for the lifting fluid, said lifting pipe having a valve mounted therein and adapted to be unseated by the suction action 15 of the lifting fluid and employing the suction to further aid in raising the fluid upwardly through said pipe.

15 Other objects and advantages reside in the special construction, combination and arrangement of the various elements forming the invention as more fully hereinafter described and claimed, reference being had to the accompanying drawings forming part hereof, wherein:

20 Figure 1 is a vertical sectional view through the well casing and tubing showing my invention arranged in operative position therein.

25 Fig. 2 is a similar view of the valve construction.

Fig. 3 is a similar view of the sliding sleeve mechanism designed to admit the lifting fluid to the pipe for the purpose of unseating the valve.

30 Fig. 4 is a transverse sectional view taken along a line 4—4 of Fig. 3.

Fig. 5 is a similar view taken along a line 5—5 of Fig. 3.

35 Referring now to the drawing wherein for the purpose of illustration we have disclosed a preferred embodiment of our invention, we provide a usual well casing 5 within which is arranged the tubing section 6, the walls of the casing and these tubings being disclosed in spaced relation.

The lower end of this tubing carries a perforated pipe section 7 adapted to admit the fluid to be lifted within the same, the opening in the upper end of said pipe section being formed into a seat upon which is snugly fitted 55 the tapered lower end 8 of the body portion 9, secured on the lower end of the lifting pipe 10.

At the tapered end 8 of the body is threadedly attached a perforated tubular fluid intake pipe section 11 extending downwardly within the pipe section 7, the lower end of which is provided with a plug 12 forming a guide for a valve stem 13 extending longitudinally through the pipe section 11 and having 60 the upper end of said stem formed into a ball 14 for engagement upon a valve seat 15 interposed between the threaded connection of the pipe section 11 and the tapered end 8 of the body. 65

70 The valve stem carries a coiled spring 16 adapted to normally maintain the ball 14 in an upward longitudinal position. The lower end of the stem extends through the plug 12 and threadedly carries nuts 17 adapted to secure the stem in adjusted position whereby to regulate the openings between the ball and the seat as well as to tensionally adjust the spring 16. 75

The body 9 immediately above its tapered 80 end 8 is externally threaded whereby to receive a pipe section 18 enclosing the body 9 with the walls thereof, arranged in spaced relation and forming a passageway 19 therebetween. The upper end of the body 9 thread-

85 edly supports a flowing plug 20 having a central opening communicating with the interior of the body, the sides of the plug overlapping the upper end of the body and having a plurality of vertically extending ducts drilled in 90 the walls of the plugs, communicating at their lower ends with the passage 19, with the upper ends thereof opening into a chamber above the plug with which the opening in the body 9 also communicates by means of the 95 central opening 21 in the plug.

The outer walls of the plug 20 form a tight fit within the bore of the upper end of the pipe section 18. A collar 23 is snugly fitted about the pipe section 18 and retained thereon 100

- in any suitable manner to prevent vertical movement with respect thereto, the inner periphery of the lower portion of the collar being reamed out as indicated at 24 to form a space passageway between the outer wall of the pipe section 18 and the inner wall of the collar, openings 25 being formed in the wall of the pipe section 18 communicating with said passageway, said openings being adapted 5 to be closed by a sleeve 26 interposed between the walls of the pipe section and the collar. A coiled spring 27 is arranged in the passageway immediately above this sleeve adapted to normally retain the latter downwardly 10 in closed position with respect to the opening. Pins 28 carried by the collar, engage the lower edge of the sleeve to prevent the same from sliding downwardly through the flared opening 29 formed at the lower edge of the collar. A pin 30 carried by the section 18 also engaged a lower edge of the collar to prevent any possibility of the same from moving in a downward direction.
- A bridge 31 comprising a transversely disposed pipe section is arranged within the bore of the body 9 near the upper end thereof, said bridge having a duct extending therethrough with its opposite end communicating with the passageway 19 formed between the walls of 15 the body 9 and the pipe section 18. An opening 32 is formed in the bridge adapted to discharge fluid therefrom in an upper direction, and in vertical alinement with the opening 21 formed in the fluid plug 20.
- In the operation of the device, after the casing with the tubing and lifting pipe have been lowered in the well containing the fluid which is to be raised therefrom, the fluid used as the lifting agent, which may be either air, 20 gas, oil or water, is then forced into the casing between the same and the tubing under pressure and admitted through ports 33 to within the tubing adjacent the lifting pipe.
- The fluid is forced downwardly in the tubing and through the flared opening 29 in the collar 23 so as to raise the sliding sleeve 26 upwardly thereby admitting the fluid into the pipe section 18, through the opening 25. The fluid which is to be lifted, entering the 25 lower end of the lifting pipe through the perforated section 11 is drawn upwardly through the body 9 by reason of the suction created by the upward passage of the lifting fluid through the ducts 22 of the flowing plug and the opening 32 in the bridge 31.
- The lifting fluid and the fluid which is to be lifted thus intermingle above the flowing plug 20 and together pass upwardly through the lifting pipe 10. Should the pressure exerted upon the lifting fluid be cut off, the spring 27 will operate to move the sliding sleeve 26 so as to close the openings 25, thus preventing the lifting fluid from entering the well casing, and should the flow of the fluid 30 from the well be cut off, the ball valve 14 will

immediately close upon downward compression, preventing the discharge of the fluid downwardly from the lower end of the pipe.

It is obvious that the invention is susceptible to various changes and modifications without departing from the spirit thereof or the scope of the appended claims, and we accordingly claim all such forms of the device to which we are entitled.

Having thus described our invention, what we claim as new is:—

1. In a fluid lifting apparatus for wells, a well casing having a tubing arranged therein, a lifting pipe arranged within the tubing and having its lower ends adapted to admit the fluid to be lifted, said tubing having openings communicating with the casing, a collar carried by the lifting pipe having its lower end arranged in spaced relation therefrom, said lifting pipe having a plurality of openings arranged therein and communicating with the space formed between the collar and the lifting pipe, and a sleeve slidably carried between the collar and the lifting pipe and yieldably retained in position whereby to close said opening and adapted to be moved out of closing position by the pressure of a lifting fluid admitted within the tubing from the casing.

2. In combination, a well casing, a tubing arranged therein and having openings communicating with the casing, a lifting pipe arranged within the tubing, a valved opening carried at the lower end of said pipe and adapted to admit the fluid to be lifted to within the pipe, a pipe section carried by the lifting pipe in spaced relation therefrom to form a passage between the walls of the lifting pipe and the pipe section, a plug arranged at the upper end of said passage, a plurality of ducts formed in said plug and communicating with the passage, a bridge extending transversely of the lifting pipe near its upper ends, and having a bore formed there-through communicating with said passage, and an opening extending upwardly from the bridge and communicating with said lifting pipe, a collar arranged on the pipe section having its lower end based from the outer wall of said section, said section having openings communicating with the spaced lower end of the collar, a sleeve slidably mounted between the collar and the section, means yieldably retaining the sleeve in closed position with respect to said opening, and

adapted to be moved into open position upon the admission of fluid under pressure from the casing to within the tubing, whereby to create the suction within the lifting pipe for raising the fluid to be lifted upwardly therein.

In testimony whereof we affix our signatures.

CLAUD WILSON.
